UNITED STATES PATENT OFFICE.

LEWIS L. HYATT, OF NEW BRUNSWICK, NEW JERSEY.

DESIGN FOR RUBBER MATS.

Specification forming part of Design No. 5,983, dated July 16, 1872.

Specification describing a new and Original Design for Rubber Mats, invented by LEWIS L. HYATT, of New Brunswick, in the county of Middlesex and State of New Jersey.

The nature of my improved design for perforated India-rubber mats is clearly represented in the drawing, to which reference is made; the said design being a border, A, and a center-piece, B, as shown; said center-piece being designed to contain the name or monogram of the owner of the house to which the mat belongs.

I claim as my invention—

1. The border A, as shown.
2. I also claim the center-piece B, as shown.

LEWIS L. HYATT.
